UNITED STATES PATENT OFFICE.

ROBERT W. SCOTT, OF LEEDS POINT, NEW JERSEY, ASSIGNOR OF ONE-HALF
TO LOUIS N. D. WILLIAMS, OF OGONTZ, PENNSYLVANIA.

OPENWORK KNITTING-MACHINE.

No. 846,431.

Specification of Letters Patent.

Patented March 5, 1907.

Application filed October 4, 1906. Serial No. 337,437.

To all whom it may concern:

Be it known that I, ROBERT W. SCOTT, a citizen of the United States, residing in Leeds Point, Atlantic county, New Jersey, have invented certain Improvements in Openwork Knitting-Machines, of which the following is a specification.

This invention consists of an improvement in or modification of that forming the subject of my application, Serial No. 335,403, filed September 20, 1906.

My former invention related to a machine for forming eyelet-holes in knitted webs by transferring certain sinker-wale loops to adjoining needles; and the purpose of the present invention is to so construct such a machine as to permit any desired diversity in the distribution of the eyelet-holes throughout the knitted web.

In the accompanying drawings, Figure 1 is a vertical sectional view of sufficient of a circular-knitting machine to illustrate my present invention. Fig. 2 is an inverted plan view of the cams of the dial-cam plate of such a machine. Fig. 3 is a view showing the cams of the cylinder cam-box developed in a flat plane. Figs. 4, 5, and 6 are views, on an enlarged scale, illustrating the method of effecting the transfer of the sinker-wale loops to the adjoining needles. Figs. 7 to 12, inclusive, are views of the different forms of sinker-wale-loop-transfer devices employed in the machine shown in Fig. 1. Figs. 13 and 14 are vertical sectional views of parts of a circular-knitting machine of a different type from that shown in Fig. 1, but also embodying my invention. Figs. 15, 16, and 17 are views of the different sinker-wale-loop-transfer devices employed in said machine. Fig. 18 is an inverted plan view of one set of cams of the dial-cam plate of said machine. Fig. 19 is a view of one set of cams of the cylinder cam-box of the machine developed in a flat plane; and Figs. 20 and 21 are perspective views of modified forms of transfer devices.

The machine forming the subject of my previous application, before referred to, was provided with transfer-points which were reciprocated by suitable cams in a direction transverse to the direction of reciprocation of the needles, these transfer-points having inclined or beveled portions adjacent to their

outer ends, whereby a sinker-wale loop caught upon said outer end when the transfer-point was partially projected could by a further projection of the point be displaced laterally into the path of an adjoining needle, and when said needle was projected and entered the loop the retraction of the loop-carrying point effected the transfer of said loop to the needle. In the previous machine, however, no provision was made for any material variation in the distribution throughout the knitted web of the eyelet-holes formed by such transfer of the sinker-wale loops, the only approach to such idea being the use, in one type of machine illustrated in said application, of a notched wheel which provided, on one rotation of the machine, for the transfer of loops in different sinker-wales from those whose loops were transferred on the previous rotation.

My present invention aims at much greater diversity in the distribution of the eyelet-holes, and its essential feature consists in the use of a plurality of sets of transfer-points, each set operated by its own cam or combination of cams, whereby it is possible to produce in the knitted web a wide range of patterns, due to the formation of the eyelet-holes in said web, an extreme instance of the capabilities of my present invention being the employment of as many sets of transfer-points as there are needles in the machine, with the result that the loops of each sinker-wale can be controlled independently of the loops of every other sinker-wale of the web. In practice, however, such an extreme application of my invention will seldom, if ever, be required.

In Fig. 1 of the drawing, 1 represents a stationary bed-plate, upon which is fixedly mounted a cylinder 2 for the guidance of the various sets of transfer-points 3, said cylinder being surrounded by a cam-cylinder 4, which is secured to a bevel-wheel 5, rotatably mounted upon the bed 1 and driven in any available manner, said cam-cylinder carrying the various cams whereby vertical reciprocating movement is imparted to the transfer-points 3. Mounted upon and rotating with the cam-cylinder 4 is an arch 6 with depending spindle 7, having at the lower end a collar 8, upon which is supported a cylindrical dial 9, carrying the needles 10, where-

2

by the knitted web is produced, this dial being surmounted by a dial-cam cap 11, which is secured to the spindle 7 and rotates therewith, the dial 9 being locked to the cylinder 2 in any available manner—as, for instance, by means of engaging lugs 12 and 13 on these respective members of the machine—so that the dial is restrained from rotating with the spindle 7. The dial-cam cap 11 is provided 10 on its under side with cams for effecting the desired radial reciprocation of the dial-needles, the latter having butts for engagement with these cams in the manner common to an ordinary rib-knitting machine. The 15 cams of the dial-cam cap comprise projecting-cams 14, 15, and 16 and retracting-cams 17, 18, and 19, all operating in connection with suitable guard-cams in the manner shown in Fig. 2. The transfer-points 3 are of different 20 lengths, each transfer-point having an upper and a lower butt, and the cylinder cam-box has a single upper groove 20 for the reception of the upper butts of all of the transfer-points and as many lower grooves 21 as there 25 are different lengths or sets of transfer-points in the machine, each groove receiving the lower butts of its respective set of points. The upper groove 20 of the cam-cylinder has a projecting-cam 22 and retracting-cams 23 30 and 24, all operating in connection with appropriate guard-cams, and each of the grooves 21 has a swinging cam 25, which when raised, as shown by full lines in Fig. 3, will vertically project to a slight extent 35 from their normal or rest position, the set of transfer-points corresponding to said groove, or when depressed, as shown by dotted lines in Fig. 3, will fail to project the points from such normal or rest position.

40 The relation of the cams of the cam-cylinder to the cams of the dial-cam cap will be understood on reference to the lines *a*, *b*, *c*, *d*, *e*, *f*, *g*, *h*, *i*, and *j* in Figs. 2 and 3, the direction of movement of the cam-cylinder and dial-cam cap being as indicated by the arrows in 45 said figures and the line *b* indicating the point at which the needles 10 engage the knitting-yarn from the yarn-guide *x*. Supposing that the needles and transfer-points 50 are fully retracted, the operation of the machine when the cams 25 occupy their elevated position will, as to each transfer-point, be as follows: The transfer-point will first be projected by its cam 25 until its outer end 3^c occupies a position between adjoining needles as represented in Fig. 4, and the needles 55 will then be projected by the cam 14 to receive the yarn from the yarn-guides *x*. When the needles are retracted by the cam 17 to engage and draw stitches of the knitting-yarn, the intermediate sinker-wale loop will be engaged and held by the outer end 3^a of the transfer-point, and said sinker-wale will then be slackened by the projection of the needles 60 due to the action of the cam 15; said needles

being then again retracted by the cam 18 to an extent sufficient to withdraw their hooks to a point just behind the back of the transfer-point, as shown at the right-hand side of Fig. 1. The transfer-point is then projected 70 by the action of the cam 22 upon its upper butt, and this has the effect of bringing the diagonally-inclined member 3^b of the transfer-point into action upon the sinker-wale loop previously deposited upon its outer 75 member 3^a, thereby causing the lateral displacement of said loop, as well as a slight outward displacement of the same due to the action thereupon of the shoulder 3^c, formed at the base of the inclined portion 3^b of the 80 point, the parts being now in the relation to each other shown in Fig. 5.

The transfer-point remains in the projected position until the needle adjoining the same has by the action of the cam 16 been again 85 projected, so as to enter the sinker-wale loop which has been displaced into the path of said needle, as shown in Fig. 5, the transfer-point being then partially retracted by the action of the cam 23 of the cylinder upon the 90 upper butt of said point in order to slacken the sinker-wale loop and insure the laying of the same into the hook of the needle, the latter being then retracted by the action of the cam 19 and the transfer-point being then 95 withdrawn by the action of the cam 24 upon its upper butt, so as to cast the sinker-wale loop onto the needle, as shown in Fig. 6. When it is not desired to transfer the sinker-wale loops controlled by any particular set of 100 transfer-points, the latter may be rendered inoperative by depressing the corresponding cam 25, the result being that said transfer-points will not be projected at the point where the needles engage the knitting-yarn, and consequently the sinker-wales will be 105 formed behind said transfer-points instead of around the same, and the subsequent projection and retraction of the transfer-points by the action of the cams 22, 23, and 24 upon their upper butts will have no effect, except, perhaps, that of causing them to act as web-holders when the needles are projected by the cam 16 of the dial-cam plate.

The production of eyelet-holes in a knitted 115 web presupposes not only the formation of plain wales between the eyelet-forming wales, but also the formation of one or more regular courses of knitting between those in which the sinker-wale loops are transferred in the 120 manner before described.

The formation of plain wales between the eyelet-forming wales may be effected by so disposing or so operating the sets of transfer-points or the points of each set that one or 125 more needles will in each course of knitting intervene between those to which the sinker-wale loops are transferred, and the formation of one or more regular courses of knitting between those in which the sinker-wale loops 130

are transferred may be effected in a single-feed machine by dropping the cam 25, controlling any particular set of transfer-points, for one or more rotations of the machine 5 after said points have effected a transfer.

In that type of machine shown in Figs. 13 to 19 the conditions are the reverse of those of the machine shown in Figs. 1 to 3, the needles 10 being carried by the cylinder 2, the needle-operating cams being carried by the cam-cylinder 4, the transfer-points 3 being carried by the dial 9, and the point-operating cams being carried by the dial-cam cap 11. In the machine shown there are three sets of transfer-points and each point has but one projecting butt for the action of the cams, of which three sets are employed, as shown in Fig. 18, the cams corresponding to the cams 22, 23, 24, and 25 of the machine first described being lettered, respectively, 22^a, 23^a, 24^a, and 25^a and the same rule being observed in the lettering of the needle actuating cam shown in Fig. 19. This construction is available in the case of a multi-feed machine having a dial and a dial-cam cap of relatively large diameter which provides sufficient radial space for the location of the plurality of sets of cams employed; but where any considerable number of sets of transfer-points is desired the construction shown in Figs. 1, 2, and 3 is always preferable, since there is practically no limit to the height to which the cylinder can be carried.

In a machine of the type shown in Figs. 31 to 19 the plain courses can be formed between the transfer courses either by adjusting the cams 25^a to the inoperative position at one or more feeds or by providing transfer-cams at certain feeds only, plain work being produced 40 at the remaining feeds. If it is desired to effect spreading of the sinker-wale loops so as to engage an adjoining needle on each side of the same, this can be readily effected by substituting for the transfer-points shown other transfer-points having forked heads, as shown in Fig. 20, or by combining two transfer-points so that their diagonal portions diverge in opposite directions, as shown in Fig. 21, and the invention can also be applied to 45 machines for knitting ribbed fabric by using needles in both the cylinder and dial and alternating the transfer-points with the needles or groups of needles in the dial or cylinder, or both, suitable cams for operating the 50 needles of the cylinder and dial in order to cause them to knit being in such case provided both in the cam-cylinder and dial-cam plate. As a known means for imparting swinging or back-and-forth movement of partial rotation to a cam pivotally mounted 55 upon the cylinder I may refer to my Letters Patent No. 368,429, dated August 16, 1887, and as a known means of swinging a dial-cam I may refer to the Letters Patent of L. N. D. Williams, No. 491,911, February 14, 1893.

The transfer-points which I have shown and described are free from any hook, latch, or other obstruction such as would form part of a transfer-needle, and the sinker-wale loops can therefore be cast from the points 79 without difficulty and with the minimum amount of reciprocating movement of the points. Consequently the use of such points is always preferred, although my invention in its broader embodiments is not limited to 75 such use, but contemplates the use of transfer-needles or other transfer devices as well.

I claim—

1. The combination, in a knitting-machine, of needles, means for knitting thereupon, and means for transferring sinker-wale loops to adjoining needles to form eyelet-holes in the knitted web, said sinker-wale-loop-transfer devices being disposed in independently-operable sets. 80

2. The combination, in a knitting-machine, of needles, means for knitting thereupon, and means for transferring sinker-wale loops to adjoining needles to form eyelet-holes in the knitted web, said sinker-wale-loop-transfer devices being disposed in independently-operable sets, and cams for operating said transfer devices having, for different sets of the same, members adjustable to position for causing the transfer devices to engage the sinker-wale loops or to position which will prevent such engagement. 90

3. The combination, in a knitting-machine, of needles, means for knitting thereupon, and means for transferring sinker-wale loops to adjoining needles to form eyelet-holes in the knitted web, said transfer devices being disposed in independently-operable sets and each set being combined with a cam for moving its members into position for engaging the sinker-wales, the transfer devices of all of the sets being combined with a single set of cams for moving them to transfer position and then retracting them to position for casting their loops. 100

4. The combination, in a knitting-machine, of needles, means for knitting thereupon, and means for transferring sinker-wale loops to adjoining needles to form eyelet-holes in the knitted web, said transfer devices 105 being disposed in independently-operable sets and each set being combined with an adjustable cam for moving its members to position for engaging the sinker-wales or permitting them to remain in inoperative position, the transfer devices of all of the sets being combined with a single set of cams for moving them to transfer position and then retracting them to position for casting their loops. 115

5. The combination, in a knitting-machine, of a cylinder and dial, needles carried by the latter, means for knitting upon said needles, and means for transferring sinker-wale loops to adjoining needles to form eye 120

130

let-holes in the knitted web, said transfer devices being disposed in independently-operable sets in the cylinder of the machine.

6. The combination, in a knitting-machine, of a cylinder and dial, needles carried by the latter, means for knitting upon said needles, and means for transferring sinker-wale loops to adjoining needles to form eyelet-holes in the knitted web, said transfer devices being disposed in independently-operable sets in the cylinder of the machine, and having butts in superposed horizontal planes and each set of transfer devices having, in its respective horizontal plane, a cam for moving its members into position for engaging the sinker-wales.

7. The combination, in a knitting-machine, of a cylinder and dial, needles carried by the latter, means for knitting upon said needles, and means for transferring sinker-wale loops to adjoining needles to form eyelet-holes in the knitted web, said transfer devices being disposed in independently-operable sets in the cylinder of the machine, and having butts in superposed horizontal planes and each set of transfer devices having, in its respective horizontal plane, a cam for moving its members into position for engaging the sinker-wales, said cam being adjustable into such position that it will fail to effect such projection.

8. The combination, in a knitting-machine, of a cylinder and dial, needles carried by the latter, means for knitting upon said needles, and means for transferring sinker-wale loops to adjoining needles to form eyelet-holes in the knitted web, said transfer devices being disposed in independently-oper-

able sets in the cylinder of the machine and each device having two butts for being acted upon by its operating-cams, all of the transfer devices having butts in the same plane combined with cams for moving them to transfer position and retracting them to casting position, and each set of transfer devices having butts in its own independent horizontal plane, and a cam for acting upon said butts to project the transfer devices to position for engaging the sinker-wale loops.

9. The combination, in a knitting-machine, of a cylinder and dial, needles carried by the latter, means for knitting upon said needles, and means for transferring sinker-wale loops to adjoining needles to form eyelet-holes in the knitted web, said transfer devices being disposed in independently-operable sets in the cylinder of the machine and each device having two butts for being acted upon by its operating-cams, all of the transfer devices having butts in the same plane combined with cams for moving them to transfer position and retracting them to casting position, and each set of transfer devices having butts in its own independent horizontal plane, and a cam for acting upon said butts to project the transfer devices to position for engaging the sinker-wale loops, said latter cam being adjustable to the inoperative position.

In testimony whereof I have signed my name to this specification in the presence of two subscribing witnesses.

ROBERT W. SCOTT.
